UNITED STATES PATENT OFFICE.

JULIUS PEGEL, OF PHILADELPHIA, PENNSYLVANIA, ASSIGNOR TO JOHN BROMLEY & SONS, OF SAME PLACE.

DESIGN FOR A RUG.

SPECIFICATION forming part of Design No. 19,464, dated December 3, 1889.

Application filed November 7, 1889. Serial No. 329,587. Term of patent 3½ years.

To all whom it may concern:

Be it known that I, JULIUS PEGEL, a citizen of the United States, and a resident of Philadelphia, Pennsylvania, have invented a new and Improved Design for Rugs, reference being had to the accompanying photographic illustration, making part hereof, in which—

5 A is the ground-work of the rug; B, a middle oblong-square panel.

10 C C are flowers forming a border to the panel outside of its boundaries, and consisting

of flowers with radiating leaves. The panel itself is ornamented within its borders with a long broad cluster of flowers D E F and 15 leaves and sprays G H, as shown.

What I claim as new is—

The design for rugs, as shown.

In witness that the above is my invention I have hereunto set my hand.

JULIUS PEGEL.
